ATTORNEY

INVENTOR

UNITED STATES PATENT OFFICE.

EDWARD T. HODGES, OF HAVERHILL, MASSACHUSETTS.

PERMUTATION-LOCK.

1,239,010.

Specification of Letters Patent.

Patented Sept. 4, 1917.

Application filed September 26, 1916. Serial No. 122,275.

To all whom it may concern:

Be it known that I, EDWARD T. HODGES, a citizen of the United States, residing at Haverhill, in the county of Essex and State of Massachusetts, have invented certain new and useful Improvements in Permutation-Locks, of which the following is a specification.

This invention relates to a keyless padlock 10 and more particularly to a padlock which will be provided with dials bearing a plurality of numerals and constructed to permit the shackle of the lock to be secured in locked position or swung into unlocked position according to the disposition of certain of the numerals on the dial.

The invention also aims to provide a keyless padlock which will be of such a simple design and consist of such a minimum number 20 of parts that the manufacture of the article will be cheap and at the same time the device will retain the necessary elements of durability and usefulness.

The above and additional objects are accomplished by such means as are illustrated in the preferred embodiment and in the accompanying drawings, wherein like characters denote like or corresponding parts throughout the several views, in which:—

30 Figure 1 is a side elevation.

Fig. 2 is an edge elevation partly broken away.

Fig. 3 is a section on the line 3—3 of Fig. 2.

35 Fig. 4 is a side elevation of one of the disks looking toward the inside thereof.

Fig. 5 is a fragmentary section on the line 5—5 of Fig. 3.

40 Fig. 6 is a section on the line 6—6 of Fig. 3.

A central base plate 1 is of substantially circular formation and has integrally connected with its center the trunnions or pivots 2 upon which are rotatably mounted the

45 disks 3 and 4. The central plate 1 is provided with a cut out portion or recess 5 which is designed to receive the latch-end 6 of a shackle 7. The opposite or pivot end of the shackle is arranged in a depression 8 formed in the central plate and which is of substantially V-shaped formation and is curved at its vertex for receiving the rounded end of the shackle. Each of the disks 3 and 4 has an annular groove 9 formed

50 adjacent the edge of each disk and adapted to receive the lugs or enlargements 10 which

are integrally formed with the end of the shackle and act as means for allowing the shackle to be swung to unlocked position. It will be noted that this novel manner of 60 mounting the end of the shackle allows the central plate, disks and shackle to be assembled quickly and easily and without the necessity of providing a pintle and apertures for the shackle. An additional recess 11 is 65 formed in the central plate 1 and connects with the recess 5 for a purpose which will be presently described. Each of the disks 3 and 4 are also provided with a recess 12 which extends into the central portion of the 70 disks and connects with the annular grooves 9 and these recesses are adapted to receive the ends 13 of a blade 14 which is a part of the locking dog 15. An operating stem 16 is integrally formed with the blade 14 and 75 extends through an aperture 17 in the central plate 1. The opposite side of the blade has a stem 18 which extends into the recess 11 and receives one end of an expansion coil spring 19 the opposite end of which contacts with the end of the recess 11 and thereby normally tends to hold the blade out of engagement with the recesses 12.

The edge of the central plate 1 bears a plurality of circumferentially spaced graduations which are consecutively numbered and the edges of each of the disks 3 and 4 also are provided with circumferentially spaced graduations which are consecutively numbered and by alining certain of the numbers the notches 12 may be brought into position whereby the blade 14 may be thrust into the notches 12 by means of the operating member 16 and thereby release the latch-end of the shackle from engagement with 90 the blade 14, the latch-end 6 of the shackle being provided with a notch 6' which receives the blade 14 when the shackle is in locked position.

In reduction to practice I have found that 100 the form of my invention illustrated in the drawings and referred to in the above description, as the preferred embodiment, is the most efficient and practicable; yet realizing that the conditions concurrent with the 105 adoption of my device will necessarily vary, I desire to emphasize the fact that various minor changes in the details of construction, proportion and arrangement of parts may be resorted to, when required, without sacrificing any of the advantages of my invention, 110 as defined in the appended claims.

I claim:

1. In a permutation lock, the combination with a circular plate having rotatable disks mounted on each of its side faces, the said 5 disks and the plate having recesses extending at a tangent to their peripheries, a locking dog including a blade received in the recess in the said plate and having its ends projected beyond the sides of the plate, the 10 said disks having annular grooves for receiving the ends of the blade, the said recesses in the disks communicating with the annular grooves whereby the ends of the blade may be extended into the recesses in 15 the disks, resilient means mounted in the recesses in the plate and engageable with the plate to hold the said ends normally in the grooves, and an operating stem carried by the blade, the said plate having an opening 20 for receiving the stem whereby the latter may project beyond the periphery of the plate.
2. In a permutation lock, the combination of a circular plate having rotatable disks 25 mounted on each of its opposite faces, the said disks and the said plate having recesses extending at a tangent to their peripheries, a locking dog including a blade normally disposed in a horizontal plane and 30 having its ends projecting outwardly beyond the recesses in the said circular plate, each of the said disks having an annular groove for receiving one of the ends of the said blade, the said recesses in the disks communicating 35 with the said annular grooves, a shackle having its end adapted to be moved into the recesses in the said circular plate, the said blade carrying an operating member, the said member being projected outwardly 40 beyond the periphery of the said circular plate, a coil spring engaging the plate for normally holding the said operating member in extended position, and a stem carried by the blade and embraced by 45 the said spring.
3. In a permutation lock, the combination with a central plate having a recess formed therein and formed at a tangent to the periphery of said plate, disks rotatably 50 mounted on said plate and also provided with recesses disposed at a tangent to the periphery of said disks, said disks and said plate being provided with a plurality of graduations whereby the recesses in said 55 plate and in said disks may be moved into alignment for providing a laterally extending continuous slot of a substantial width, a

locking dog comprising a blade adapted to extend into said slot, an operating member integrally formed with the blade and extending through an aperture in the periphery of said plate, a shackle, one end of the shackle being adapted to extend into an enlarged recess in said plate which communicates with the recesses forming said slot, 60 the end of the shackle having a notch for receiving said blade, and resilient means interposed between the end of said slot and the blade of said locking dog.

4. In a permutation lock, the combination with a circular plate, rotatable disks mounted on the opposite faces of the plate, the proximate faces having annular grooves, the said plate and the said disks each having recesses disposed at a tangent and adapted to 75 be transversely aligned to establish communication between the said annular grooves, a shackle having one end provided with a notch, the shackle being pivotally mounted for permitting the said notch to be aligned 80 with the said recesses, a horizontally disposed blade, a stem projecting from one edge of the blade at the center thereof and into the said recesses in the circular plate, resilient means interposed between the ends 85 of the recesses and the edge of the said blade and embracing the said stem, and an operating member connected to the said blade.

5. In a permutation lock, the combination of a circular plate having recesses formed 90 in its periphery and rotatably carrying a disk on each of its opposite faces, said disks and said plate provided with recesses disposed at a tangent to their peripheries, with a locking dog disposed in one of said recesses 95 and adapted to be manually operated in one direction for movement into said recesses, each of said disks being provided with an annular groove for the reception of the ends of said locking dog when in inoperative position, a shackle having its pivoted end disposed within one of the recesses in said plate, and carrying lugs which project laterally into said annular grooves, the opposite end of said shackle having a notch for the reception of said locking dog, and resilient means for normally holding said locking dog in engagement with said shackle.

In testimony whereof I affix my signature in presence of two witnesses.

EDWARD T. HODGES.
